UNITED STATES PATENT OFFICE.

WILLIAM W. MINER, OF NEW HAVEN, CONNECTICUT, ASSIGNOR OF ONE-HALF
TO CHARLES S. MERSICK, OF SAME PLACE.

MANUFACTURE OF HORSESHOE-NAILS.

SPECIFICATION forming part of Letters Patent No. 415,818, dated November 26, 1889.

Application filed February 11, 1889. Serial No. 299,385. (No model.)

To all whom it may concern:

Be it known that I, WILLIAM W. MINER, of New Haven, in the county of New Haven and State of Connecticut, have invented a new

5 Improvement in the Manufacture of Horseshoe-Nails; and I do hereby declare the following, when taken in connection with accompanying drawings and the letters of reference marked thereon, to be a full, clear, and 10 exact description of the same, and which said drawings constitute part of this specification, and represent, in—

Figure 1, a side view of the nail complete; Fig. 2, an edge view of the same; Fig. 3, the 15 rolled blank preparatory to flattening; Fig. 4, devices for rolling the blank; Fig. 5, devices for flattening the blank and finishing the nail; Fig. 6, a face view of the die portion in which the blank is rolled.

20 This invention relates to an improvement in the manufacture of the class of nails used for securing horseshoes and known in the trade as "horseshoe-nails."

The blanks for making horseshoe-nails are 25 formed to the general outline of a horseshoe-nail, always with a flat surface. Subsequently to such formation of the blank the proper curvature is given throughout and the tips beveled and pointed. Complicated machinery 30 is necessary for this work and embraces numerous operations.

The object of my invention is a simple and cheap method of manufacture, whereby many of the operations now required will be dispensed with; and the invention consists in 35 first rolling the body of the blank of a tapering form round in transverse section, the taper distributing the requisite quantity of metal for different parts of the body, then 40 flattening the body by pressure to give it the required thickness, such flattening throwing the metal to the sides to give the requisite width, and as more fully hereinafter described.

In the formation of the nail I take a round, 45 square, or other suitably-shaped rod of the required transverse area for the production of the nail and roll the rod between surfaces which together are the shape the reverse of that required to be produced.

50 In Fig. 4, A represents one plate, and B a

second plate, having their adjacent faces shaped so as to form a recess C between them corresponding in section to the shape of the blank to be produced. This blank, as seen in Fig. 3, is to be round in transverse section, 55 but tapering, the taper being such as to distribute the metal throughout the length of the nail, and so as to give the requisite quantity required at such different parts for the finished nail.

Under a practical construction of the method of rolling the plates A B reciprocate, but in opposite directions, and so that a blank of metal placed between them will be rolled and delivered from the plates, the metal assuming 65 the shape of the space between the plates at the delivery. This method of rolling metal is well known, and does not require particular description. After the blank D, Fig. 3, has been thus produced by the rolling operation it is flattened by suitable dies or rolls.

As an illustration of the rolls as applied to flattening the nail, E F represent a pair of rolls arranged to work between two surfaces G H. In the lower surface is a cavity b, corresponding to the shape of the nail, its bevel point, as seen in Fig. 5, and the taper, as seen in Fig. 6, and also the shape of the head. The opposing surface G serves as a guide to press upon the rollers and hold them in 75 proper contact with the blank to be rolled throughout the length of the nail, and so that the round blank introduced into the cavity of the part H and the rolls passed over the blank from point to head will completely finish the nail, beveling, pointing, and flattening it. The rolls, E F are supported from a carriage I, and reciprocating movement is imparted to the said carriage, the means for such reciprocating movement (not shown) being immaterial to the invention.

The amount of metal which is put into the blank in the blank forming or rolling operation is such that when flattened, as I have described, the required width of the nail throughout its length will be attained. The blank will be pointed and finished in the operation of flattening.

The illustration which I have given for flattening the blank will be sufficient to enable 100

others skilled in the art to flatten the blank by other means—such, for instance, as between dies.

In the nail thus produced the metal is very solid and compact. The operation gives to the nail the required temper, and it is much tougher and less liable to split and more perfect than can be produced by the usual forging operation and subsequent trimming, pointing, and bending.

The machinery for rolling, as well as the machinery for flattening, may be automatic. Such automatic machinery will constitute the subject of another application.

15 The body of the nail below the head—say as below the line *a* of Fig. 3—may be rolled into tapering shape, as I have described, without rolling the head, the head being otherwise shaped. This rolling operation will give

to the nail the solidity, toughness, and temper 20 which are desirable.

I do not claim, broadly, making the body of a horseshoe-nail round and then flattening that round body, as such, I am aware, is not new.

25

I claim—

The method of manufacturing horseshoe-nails which consists in first rolling the blank round in transverse section throughout, but tapering, and so that the requisite quantity 30 of metal for the formation of the nail is distributed through the head and body, then flattening the body and head, substantially as described.

WILLIAM W. MINER.
